UNITED STATES PATENT OFFICE.

THOMAS MILLWARD, OF SAN FRANCISCO, CALIFORNIA.

CARBONATING-MACHINE.

1,177,531.

Specification of Letters Patent. Patented Mar. 28, 1916.

Application filed November 19, 1914. Serial No. 872,956.

To all whom it may concern:

Be it known that I, THOMAS MILLWARD, a citizen of the United States, residing at San Francisco, in the county of San Francisco, 5 State of California, have invented a new and useful Carbonating-Machine, of which the following is a specification in such full and clear terms as will enable those skilled in the art to construct and use the same.

10 This invention relates to a machine for carbonating beverages and its object is to produce a machine which will use as little power as possible above that stored in the tank from which the supply of CO₂ under 15 pressure is obtained.

An embodiment of the invention is shown in the drawing in which the same reference numeral is applied to the same portion throughout, but I am aware that there are 20 many modifications thereof.

Figure 1 is a side elevation partly in section of the apparatus, Fig. 2 is a side elevation partly in section of one of the check valves used in the apparatus, and Fig. 3 is a 25 side elevation partly in section of one of the mechanically operated valves used in the apparatus.

The apparatus consists of a storage receptacle 1, a pump cylinder 2, charging cylinder 30 3 and the frame work 4 and 5 necessary to support the several parts. The pump cylinder has a pipe 6 connected with one end thereof, which pipe extends into a T 7, which T is connected with a pipe 8 in turn connected with the check valve 9, which latter 35 is connected by means of the nipple 10 to the bottom of the storage cylinder 1, which storage cylinder may be of such dimensions as is deemed necessary. Also connected to the 40 T 7 is a pipe 11 which extends into the check valve 12.

The check valves 9 and 12 are constructed as illustrated in Fig. 2 with a side plug 13 through which the valve proper 14 may be 45 placed in its seat and said valve is provided with a spiral spring 15 which holds it seated. It is to be observed that the valve 9 is installed in the position indicated in Fig. 2 so that at any time it is possible for the liquid 50 in the storage tank 1 to pass therethrough to the cylinder 2, while the valve 12 is installed in the reverse position, thereby preventing the liquid in the pipe 16 from being forced downwardly into the cylinder 2, while 55 at the same time leaving the pump piston

free except for the pressure in the cylinder 3 to force the fluid up into the charging cylinder. A pipe 16 is connected with the charging cylinder near the top thereof and above a set of baffle plates 17, 18 and 19, 60 which plates are provided with openings to cause the liquid to pass to the lower portion of the cylinder in a finely disseminated condition. The cylinder 3 has a pipe 20 which is connected by means of a suitable union 21 65 with the pipe 22 leading from the regulating valve 23, which valve is used for determining the pressure in the cylinder 3 of the CO₂ delivered from the tank 24, such tanks being commonly supplied to the trade in a suitably 70 high pressure of several hundred pounds or more per square inch.

At the front the cylinder 2 is provided with a stuffing box 25 through which the piston rod 26 operates, said piston rod having 75 the piston 27 thereon. The piston is operated by means of a lever 28 connected to the piston rod by means of the link 29, said lever being supported by a bracket 30 carried by the front end of the cylinder 2 80 and projecting forwardly and upwardly therefrom.

A pipe 31 connects the bottom of the cylinder 3 with the valve 32. On the opposite side this valve is connected with the pipe 33, 85 which extends around to the front of the cylinder 2, said valve preventing the liquid in the cylinder 3 from passing to the cylinder 2 unless the valve is positively opened by the operating cams.

Connected with the front and top of the cylinder 2 is a pipe 34 which pipe extends into the valve 35, said valve being so set as to prevent the escape of fluid from the cylinder 2 unless expressly lifted by its operating 95 cam. At the bottom the cylinder 2 is provided with a pipe 36 which pipe extends into a valve 37 substantially identical with the valves 32 and 35; note particularly the interior construction of said valves in Fig. 100 3. These valves have threaded ends as indicated at 38 and 39 and have a vertically movable valve gate 40, which valve gate is connected with a rod 42 passing through a stuffing box 41. The valve gate has suitable 105 guide ribs 43 to prevent the valve from being misplaced from its proper position when the valve is operated.

The valve 37 is provided with a depending spout 44. All of the valve stems extend 110

upwardly above the slide rod 45, said slide rod moving along guides 46, 47 and 48. The slide rod has a slot 49 at its front end and on its upper side it is provided with three cams 50, 51 and 52, which cams lift the rollers 53, 54 and 55 carried by the several rods 42. It will be observed that the rollers 53 and 54 are now shown in the raised position while the roller 55 is shown in the lowered position. It is also to be noted that the length of the slot 49 is determined by the movement of the slide rod necessary to give the movement to the cams to lift the rollers 53 and 55 and by the actual movement of the pin 56 on an operating lever 28 which moves the slide rod.

The operation of the apparatus is as follows: Assuming the receptacle 1 to be of such size as to supply a number of charges 20 of water to the cylinder 2, and the tank 24 to be charged with CO_2 under pressure, it will be seen that in the position indicated in Fig. 1 that the valve on the pipe leading from the bottom of the receptacle 3 is closed. 25 The check valves 9 and 12 respectively open down and up so that on the first stroke of the piston 27 water will flow down through the valve 9 and into the cylinder 2. Near the end of the stroke the valve 37 and valve 30 35 will be closed while just after that the valve 32 will be opened thereby making the gas pressures in the receptacle 3 and cylinder 2 equal, the check valve 12 preventing the liquid in the pipe 16 from exerting any pressure on the liquid in the cylinder 2. While the pressure is the same in the receptacle 3 and cylinder 2 the hand lever is operated to transfer the liquid in the cylinder 2 up through the valve 12 and pipe 16 40 to the perforated plates 17, 18 and 19 where the liquid will be intimately mixed with the CO_2 , a portion of said gas going into the liquid. When the liquid has been transferred while under pressure from one receptacle to the other the valve 32 will be closed, whereupon the sniff valve 35 and valve 37 will be opened in the order named. At this time the piston may be operated to draw in a charge of fresh liquid discharging 45 the same quantity of carbonated liquid, or the carbonated liquid may be allowed to run out of the cylinder as it will, after which a charge of fresh liquid may be drawn in and the process repeated at will. As the water or other liquid passes through the baffle plates 17, 18 and 19 it is in a finely divided condition and in that condition absorbs a sufficient quantity of CO_2 to become highly impregnated therewith, and when the piston 50 is moved to the left it will draw substantially the same amount of carbonated water out of the cylinder 3 as is forced thereinto 55 through the valve 12 and this water can be drawn from the cylinder 2 when the valve 60 65 37 is open, thereby permitting it to escape

therefrom by gravity or by pushing it out by returning the piston 27 to the right hand end of the cylinder.

Having thus described my invention what I claim as new and desire to secure by Letters Patent of the United States, is as follows, modifications within the scope of the claims being expressly reserved:

1. A carbonating machine comprising a pump cylinder, a liquid supply cylinder connected with the pump cylinder, a charging cylinder, a connection from the pump cylinder to the charging cylinder, two valves interposed between the pump cylinder, the supply receptacle and the charging cylinder, a pipe connection between the lower portion of the charging cylinder and the opposite end of the pump cylinder, a valve in said connection, an outlet valve connected with the lower portion of the pump cylinder, and a pressure relief valve connected with the upper portion of the pump cylinder.

2. A carbonating machine comprising a pump cylinder, a liquid supply cylinder connected with the pump cylinder, a charging cylinder, a connection from the pump cylinder to the charging cylinder, two valves interposed between the pump cylinder, the supply receptacle and the charging cylinder, a pipe connection between the lower portion of the charging cylinder and the opposite end of the pump cylinder, a valve in said connection, an outlet valve connected with the lower portion of the pump cylinder, a pressure relief valve connected with the upper portion of the pump cylinder, and means to close the valves in the connection between the lower portion of the charging cylinder and the pump cylinder and to open the relief valve and the discharge valve when a charge of liquid is to be drawn from the pump.

3. A carbonating machine comprising a pump cylinder, a liquid supply cylinder connected with the pump cylinder, a charging cylinder, a connection from the pump cylinder to the charging cylinder, two valves interposed between the pump cylinder, the supply receptacle and the charging cylinder, a pipe connection between the lower portion of the charging cylinder and the opposite end of the pump cylinder, a valve in said connection, an outlet valve connected with the lower portion of the pump cylinder, a pressure relief valve connected with the upper portion of the pump cylinder, a supply pipe for the charging gas connected with the charging cylinder, and means to close the valve in the connection between the lower portion of the charging cylinder and the pump cylinder and to open the pressure relief valve and the discharge valve when a charge of liquid is to be withdrawn from the pump cylinder.

4. A carbonating machine comprising a pump cylinder having a solid piston, an operating lever connected with said pump piston, a liquid supply receptacle connected with one end of the pump cylinder, a charging cylinder, a connection from that end of the pump cylinder to the charging cylinder, two valves interposed between the pump cylinder and supply receptacle and charging cylinder, a pipe connection between the lower portion of the charging cylinder and the opposite end of the pump cylinder, a valve in said connection, an outlet valve connected with the lower portion 10 of the pump cylinder, a pressure relief valve connected with the upper portion of the pump cylinder, and an operating slide connected with the lever for operating the pump piston and the three last mentioned 15 valves.

5. A carbonating machine comprising a pump cylinder, a solid piston therein, an operating lever connected with said piston for the movement thereof, a liquid supply 20 receptacle, a charging receptacle, suitable valve connections between one end of the pump cylinder and the liquid supply receptacle and charging receptacle, a pipe connected with the charging receptacle for the supply of gas under pressure thereto, a pipe 25 connected with the lower end of the charging receptacle and the opposite end of the pump cylinder, a valve in said pipe, a pressure relief valve for the pump cylinder, a discharge valve therefor, and a slide rod 30 for operating the three last mentioned valves from the lever for operating the piston.

6. A carbonating machine comprising a 35 pump cylinder, a liquid supply receptacle

and a charging cylinder having valved pipe connections with the pump cylinder, a pipe connection for supplying gas under pressure to the charging cylinder, a pipe connecting the lower portion of the charging cylinder 45 and the opposite end of the pump cylinder, a valve in the latter pipe, a pressure relief valve, a discharge valve for the pump cylinder, a lever for operating the pump piston, a slide rod operated by said lever, and 50 cams carried by said slide rod adapted to open the valve in the pipe leading from the charging cylinder to the pump cylinder when the pressure relief valve and the discharge valve are closed and vice versa. 55

7. A carbonating machine comprising a pump cylinder having a solid piston therein, an operating lever, connections between the piston and operating lever, a liquid supply receptacle, a charging cylinder, pipe 60 connections between the liquid supply receptacle, the charging cylinder and pump cylinder, a pipe for supplying gas under pressure to the charging cylinder, a pipe extending from the lower portion of the 65 charging cylinder to the pump cylinder, a valve in said pipe, a pressure relief valve in the pump cylinder, an operating slide rod for said valves having a slot therein, which rod is moved near the end of the 70 stroke of the operating lever to open or close the three last mentioned valves.

In testimony whereof I have hereunto set my hand this 12th day of Nov. A. D. 1914, in the presence of the two subscribed 75 witnesses.

THOMAS MILLWARD.
